UNITED STATES PATENT OFFICE.

FREDERICK K. LAWRENCE, OF CHICAGO, ILLINOIS.

MULTIPLE-SOCKET HEAD.

1,360,121.

Specification of Letters Patent. Patented Nov. 23, 1920.

Application filed November 14, 1919. Serial No. 337,950.

To all whom it may concern:

Be it known that I, FREDERICK K. LAWRENCE, a citizen of the United States, residing at Chicago, in the county of Cook and State of Illinois, have invented a certain new and useful Improvement in Multiple-Socket Heads, of which the following is a specification.

My invention relates to wrenches and is particularly useful as a rim wrench for the wheels of motor vehicles. The object of the invention is to provide a multiple socket head which may be used in different positions with a single turning tool or brace, and yet is itself so formed that after the nut has been "started" or loosened, it affords an advantageous handle which the operator may grasp to further unscrew the nut after it has been loosened. In applying nuts, conversely, the device constitutes both a complete wrench and handle so long as the nut does not require too much torque, after which a separate turning tool may be applied. Ancillary to the above stated object it is my purpose to so construct the device that the axis of the turning tool, when in use, will be in line with the axis of the nut engaged. Another object of the invention is to so adapt the multiple socket head that it may be operated by a turning tool, the socket whereof is of a still different size, to take a nut differing in size from all the others. This increases the number of sizes to which the tool as a whole is applicable. Another object is to provide a multiple socket head so constructed as to coöperate with either a socket form or stud form of wrenching tool. Another object of the invention is to so construct the device that the force of the separate turning tool, when one is used, will be applied to a point in close proximity to the point where the socket applies its power to the nut. Still another object is to so design the device that it may combine strength with lightness of weight.

I obtain my objects by the mechanism illustrated in the accompanying drawings in which—

Figure 1 is a side view of the device, one of the sockets being shown in axial section.

Fig. 2 is an edge view of the parts shown in Fig. 1, certain portions being broken away to reveal the parts within.

Fig. 3 is a perspective view of one of the two halves of the spider.

Fig. 4 is a sectional view taken on the line 4—4, Fig. 2.

Fig. 5 is a perspective view showing the usual and preferred socket form of wrenching tool in distinction to the stud form shown in Fig. 6.

Fig. 6 is a side view of the stud form of acting head instead of the socket form shown in the other figures.

Like numerals denote like parts throughout the several views.

In the form shown in Figs. 1 to 4 inclusive the device has three acting heads in the form of sockets 1, 2, and 3, all of different sizes, thus enabling the device to accommodate itself to nuts or bolts of at least three different sizes. At its inner end each socket has another socket 4, 4, 4 all of the latter being of the same size both internally and externally and therefore all adapted to engage the same size turning tool. To take fullest advantage of my invention the sockets 4 are so formed externally that they fit into a turning tool 5, the socket 5^a whereof is of a different size from any of the sockets 1, 2 or 3. The result is that, including the turning tool, the operator is furnished with four different sizes of sockets.

In the present instance these three acting heads or sockets 1, 2, 3 are arranged with their axes all lying in the same plane, 120° apart, and radiating from a common center, and they are held in this position by a frame or spider which, according to the special design shown, is formed in two like parts 8, 8. One of these parts is shown in perspective in Fig. 3. By preference these half spiders are of sheet metal and are spot welded, riveted or otherwise rigidly fastened to the socket members. The half spiders engage opposite sides of the socket members far enough from the inner end to afford adequate bearing surface for the socket 5^a of the turning tool. They are cut away at the central portion 8^a whereby a considerable space is formed to accommodate the acting head of the turning tool. Consequently it may be said that the turning tool passes through the spider in reaching the socket member which it is to engage.

As above indicated, the turning tool may be also of the stub type 6 so as to enter inside of the sockets 4. A turning tool of this latter type is indicated in Fig. 6.

Operation: By inspecting Fig. 1 it will be evident that when socket 2, for example, is

in engagement with a nut, the sockets 1 and 3 range themselves in such manner as to form a very convenient handle by which the device may be grasped and rotated. In fact 5 the two branches temporarily out of engagement with the nut form such a good handle that the operator may, without much effort, exert so much torque that in many cases no other turning tool will be required. But 10 when a high degree of torque is required the operator employs a supplemental turning tool in the form of a brace or similar device. When such turning tool is required the acting end of it is passed through the body of 15 the spider, and its acting head is made to engage the inner end of the very member which is in engagement with the nut. Consequently the power of the turning tool will be applied at a point close to the nut. This 20 has at least two advantages: First, it enables the operator to more easily and certainly keep the socket in engagement with the nut, and second, it gives the tool greater strength in proportion to the strength and 25 thickness of the metal employed. In other words, the strength of the metal of the socket member is more efficiently utilized by applying the power of the turning tool at a point close to the nut than if the power were 30 applied at a distance, or if the power were applied to the spider instead of to the acting 35 socket member.

Having thus described my invention what I claim as new and desire to secure by Letters Patent, is:

1. A wrenching tool having a body and three branches terminating in acting heads adapted to engage an object to be turned, and a turning tool longitudinally insertible 40 into said body for attachment and longitudinally retractable for ready detachment and removal, the axis of the turning tool being in line with the axis of the temporarily acting head and the axes of the heads 45 all lying in the same plane and radiating from a common center and arranged one hundred and twenty degrees apart whereby when the turning tool is withdrawn, the two temporarily non-acting heads are in convenient position to be grasped by the operator and access to them is unobstructed.

2. A wrenching tool having three acting heads with their axes in the same plane and radiating approximately from a common 55 center and approximately at equal angles, the center of the tool being chambered and having openings in line with the axis of each of the acting heads, and a turning tool adapted to pass into said openings and

adapted to engage the acting heads at a 60 point contiguous to the point of application of power of said acting heads.

3. A wrenching tool having three separate acting heads arranged with their axes in the same plane, radiating from a common 65 center and approximately at an angle of 120 degrees apart, the inner end of each acting head being adapted to be directly engaged by a turning tool, and a spider for holding said acting heads in the position 70 specified, said spider being hollow and having openings in line with the axes of the respective acting heads for accommodating the turning tool.

4. In combination, a turning tool and a 75 wrenching tool having three socket members arranged with their axes in the same plane approximately 120 degrees apart, the inner end of each of said socket members being adapted to be engaged by said turning tool, 80 and a frame for holding said socket members in the position specified, said frame having openings in line with the axes of the respective socket members for permitting the turning tool to directly engage the inner 85 end of the socket members.

5. The combination with a turning tool of a wrenching tool having three acting members arranged with their axes in the same plane approximately 120 degrees apart 90 and radiating from a common center, each acting member being socketed at the outer end for the reception of a nut and socketed at the inner end for the reception of the end of the turning tool, and a frame for holding 95 said acting members in the position specified, said frame having openings in line with the axes of the respective socket members for permitting the turning tool to enter the inner socketed end of said acting members.

6. A wrenching tool having three socket members having sockets of different sizes and arranged with their axes all in the same plane, approximately 120 degrees apart, the 105 inner ends of the socket members being of the same size externally and of such size as to fit into a socket different in size from any one of the socket members, and a spider for holding the socket members in the position 110 specified, said spider having an opening in line with the axis of each of the socket members whereby each socket member may be directly engaged by a socketed turning tool.

In witness whereof, I have hereunto subscribed my name.

FREDERICK K. LAWRENCE.
